UNITED STATES PATENT OFFICE.

JOSEPH F. KELLER, OF NEW YORK, N. Y.

DESIGN FOR A STANDARD FOR DIE-SINKING MACHINES.

53,073.

Specification for Design.

Patented Mar. 11, 1919.

Application filed November 30, 1917. Serial No. 204,778. Term of patent 7 years.

To all whom it may concern:

Be it known that I, JOSEPH F. KELLER, a citizen of the United States, and a resident of New York, New York county, State of New York, have invented a new, original, and ornamental Design for a Standard for Die-Sinking Machines, of which the following is a specification, reference being had to the accompanying drawing, forming part thereof, in which—

Figure 1 represents a front view; Fig. 2 a

top plan view; and Fig. 3 an elevation taken from the right of the standard of the new design.

I claim:

The ornamental design for a standard for die sinking machines, as shown.

In testimony whereof I have hereunto set my hand.

JOSEPH F. KELLER.
